CANOPY FLANGE FOR VALVES

Stephen A. Young, Delphi, Ind.

Application January 30, 1948, Serial No. 144,157

Term of patent 14 years

(Cl. D91—3)

To all whom it may concern:

Be it known that I, Stephen A. Young, a citizen of the United States, residing at Delphi, in the county of Carroll and State of Indiana, have invented a new, original, and ornamental Design for a Canopy Flange for Valves, of which the following is a specification, reference being had to the accompanying drawings, forming part thereof.

In the drawings, Fig. 1 is a top plan view of a canopy flange for valves, showing my new design. Fig. 2 is an elevational view thereof.

I claim:

The ornamental design for a canopy flange for valves, as shown.

STEPHEN A. YOUNG.
